To all whom it may concern:

Colcord, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the dress shown in Fig. 1 illustrating one of the lace appliqués in detail.

The characteristic feature of my design resides in the combination on the specific dress disclosed of the specific lace appliqués arranged on the skirt and on the sleeves as indicated on the drawing.

I claim:

The ornamental design for a dress, substantially as shown and described.

CARL H. COLCORD.
